(57) **CLAIM**

The ornamental design for a flower pot cover, as shown and described.

DESCRIPTION

FIG. 1 is a perspective view of a flower pot cover showing our new design;

FIG. 2 is a front elevational view thereof.

FIG. 3 is a rear elevational view thereof.

FIG. 4 is a side elevational view thereof.

FIG. 5 is an elevational view of a side opposite that shown in FIG. 4.

FIG. 6 is a bottom plan view thereof; and,

FIG. 7 is a top plan view thereof.
